UNITED STATES PATENT OFFICE.

WILLARD C. BARNES, OF SOUTH WEYMOUTH, MASSACHUSETTS.

FEED-WATER HEATER FOR BOILERS.

968,023.

Specification of Letters Patent. Patented Aug. 23, 1910.

Application filed March 15, 1909. Serial No. 483,389.

To all whom it may concern:

Be it known that I, WILLARD C. BARNES, a citizen of the United States, residing in South Weymouth, in the county of Norfolk and State of Massachusetts, have invented 5 an Improvement in Feed-Water Heaters for Boilers, of which the following description, in connection with the accompanying drawings, is a specification, like letters on the drawings representing like parts.

This invention relates to a feed-water heating system for boilers, and has for its object to provide a simple and efficient system with which the feed water may be heated by waste heats from the fire box, and with which a circulation of water may be established through the feed water heater and the boiler when the supply of cold water to the heater is cut off.

20 The feed water heater may and preferably will be of a novel construction as will be described, to afford protection to and offer a support for the masonry at the rear of the boiler.

25 These and other features of this invention will be pointed out in the claims at the end of this specification.

Figure 1 is a vertical longitudinal section and elevation of a boiler provided with a 30 feed water system embodying this invention. Fig. 2, a plan view of the boiler and feed water heater shown in Fig. 1, with the setting in section, and Fig. 3, a vertical transverse section on the line 3—3, Fig. 1, looking toward the right.

Referring to the drawings, *a* represents 35 a fire tube boiler of any suitable or usual type, which is supported by and located in a setting *b* of masonry of any suitable construction and provided at its front end with the usual fire box *c*, grate bars *d*, ash-pit *e*, and bridge wall *f*, and having at its rear end a chamber *g* formed by the rear end 40 of the boiler and the top and rear walls *h*, *i*, of the setting.

The chamber *g* in accordance with this invention, has located in it a feed water heater, preferably made as herein shown and consisting of two enlarged substantially 45 parallel pipes or headers 10, 12, of steel or other suitable metal, which are joined by a plurality of substantially arch-shaped pipes or tubes 13.

The headers 10, 12 are shown in the present instance as horizontally arranged and

supported upon shoulders or shelves 15 in the side walls of the chamber *g* (see Fig. 3).

The feed water heater is connected with a source of cold water supply and in practice it will be connected with the outlet pipe 60 16 of a feed water pump (not shown), but of any suitable or usual construction, such as now commonly employed with feed water heaters.

The outlet pipe 16 is located at the front 65 of the boiler and is connected with the header 10 by a pipe 17 extended alongside of the boiler and forming the water inlet pipe for the feed water heater. The pipe 17 is also connected at its front end by a pipe 70 19 with the front end of the boiler near the bottom of the same.

The header 12 is connected by a pipe 20 with the rear end of the boiler substantially 75 near the middle of the same and above the level of the point of connection of the pipe 19 with the front of the boiler.

The outlet pipe 16 for the pump is provided with a valve 21, by means of which the supply of cold water by the pump may 80 be cut off or interrupted when the boiler has been supplied with water to the desired or required level.

In operation with the apparatus as thus far described, the valve 21 is opened when 85 the water in the boiler falls below a predetermined level and cold water is forced by the pump through the pipes 16, 17 into the header 10, from which it passes through the pipes 13 to the header 12, and thence 90 through the pipe 20 into the boiler. The water in its passage through the heater located in the chamber *g* is subjected to the waste heats from the fire box and is highly heated by said waste heats, which are of 95 sufficient temperature to raise the water to near the boiling point, and in some instances are sufficient to convert the feed water into steam.

It will be observed that the feed water 100 heater is located in the upper part of the chamber *g* and in the hottest part of the same, and that the said chamber is substantially filled by the heater, so that the latter is constantly exposed to and practically enveloped by a body of waste gases, which are checked or dammed up in said chamber on their passage into the fire tubes of the boiler, thereby affording opportunity for the water in the heater in said chamber to 110

abstract a maximum heat from, said gases, with corresponding efficiency in heating the feed water.

When the valve 21 is closed, the feed water heater is protected from the heat of the waste gases and prevented from being burned out by a circulation of the water through the heater and boiler, which is automatically established by the difference in level of the pipes 19, 20, and the difference in temperature of the water in the heater and the lower part of the boiler.

The circulation of water under the conditions just described is from the lower part of the boiler through the pipes 19, 17, to the heater in the chamber *g*, and thence through the pipe 20 into the boiler at a higher level than the pipe 19. The boiler may be provided with the usual blow-off pipe 30 connected with its bottom, and provision is also made for draining or blowing off of the feed water heater, which is accomplished by connecting one or both headers with a blow off pipe 30 for the boiler by a pipe 31 extended through the rear wall *i* of the setting and connected with the pipe 30, which is also extended through the rear wall *i*.

By reference to Figs. 1 and 3, it will be seen that the arch-shaped pipes or tubes 13 support the top wall *h* of the chamber *g*, and also that the location of the feed water heater in the said chamber protects the walls of the same from the waste heats.

In the present instance, the feed water heater is shown with the headers arranged horizontally, but it is not desired to limit the invention in this respect, as the said heater may be set substantially at right angles to the position shown, namely, with the headers vertically arranged.

I may prefer to use a feed water heater of the construction shown, but I do not desire to limit the invention in this respect, as the feature of the circulation for the protection of the heater when the feed water supply is cut off may be used to advantage with other forms of heaters.

In practice the heater will preferably be connected with the cold water supply as described, but it is not desired to limit the invention in this respect, as this connection may be omitted, and the heater connected with the boiler for the circulation of water as described.

The pipe 19 is provided with a check valve 34 of any suitable construction for preventing the cold water passing into the boiler through the pipe 19 and for permitting the water from the boiler to flow through the pipe 19 to the heater when the cold water supply is cut off.

It will be observed that the pipe 17 which supplies the cooler water to the heater, is connected with the front of the boiler

through the pipe 19 near the bottom of said boiler, and is extended rearwardly within the setting and is connected with the heater above the level of the bottom of the boiler. As a result, a most efficient apparatus is obtained, for the reason, that a most effective circulation of the water is obtained when the cold water supply is shut off, because the cooler water taken from the boiler at its front end is exposed to heat and to a substantially progressive heat from the point where it leaves the boiler to the point where it again enters the boiler. Furthermore, it will be noticed that the pipe 17 is connected with the heater above the level of the bottom of the boiler, with the result that the circulation is effectively maintained by the heat alone and the flow of water is practically continuously upward from the front to the rear of the boiler.

It will be observed that the blow-off pipe 30 for the boiler and the drainage pipe 31 for the heater are independent of the circulating system formed by the heater, and the pipes 19, 17, and 20, and that said blow-off and drainage pipes are extended through the rear wall *i* of the setting, which enables each boiler of a battery of boilers to be provided with an auxiliary heater, which is connected with its boiler to form a circulating system including both, as the boilers of the battery which are between the boilers adjacent to the side walls of the setting, can be drained and blown off into a common mud drum located outside of the setting, without interfering with the circulation of water in the other boilers of the battery.

Claims.

1. The combination with a boiler setting and a boiler supported thereby to form a chamber between the rear end of the boiler and the rear and top walls of the setting, of a feed water heater located in said chamber and exposed to the waste heats from the fire box of the boiler, a supply pipe for cold water located at the front of the boiler, a pipe connecting said supply pipe with the lower part of the boiler at the front thereof, a pipe extended longitudinally of the setting within the same and connecting said supply pipe directly with the feed water heater, a pipe connecting the feed water heater with the rear end of the boiler above the level of the pipe connected with the front end of said boiler, a valve in the said supply pipe to control the supply of cold water to the heater, and a blow-off pipe for the boiler independent of the circulating system, which includes the heater and boiler, substantially as described.

2. The combination with a boiler setting and a boiler supported thereby to form a chamber between the rear end of the boiler and the rear and top walls of the setting, of a feed water heater located in said chamber

- and exposed to the waste heats from the fire box of the boiler, a supply pipe for cold water located at the front of the boiler, a pipe extended longitudinally of the boiler 5 within the setting and connecting the said supply pipe directly with the said heater for the passage of cold water directly into the heater, a pipe connecting the longitudinally extended pipe with the water space of the 10 boiler, a pipe connecting the heater with the boiler above the level of the last mentioned pipe, a valve in said supply pipe, a drainage pipe connected with the bottom of the boiler and extended through the rear 15 wall of the setting, and a drainage pipe for the heater extended through the rear wall of the setting, substantially as described. 15
3. The combination with a boiler setting and a boiler supported thereby to form a 20 chamber between the rear end of the boiler and the rear and top walls of the setting, of a feed water heater located in said chamber and connected within the setting with the boiler for the circulation of cold water there- 25 through, and with a supply for cold water, a valve controlling the supply for cold water, a drainage pipe for said boiler extended through the rear wall of the setting, and a drainage pipe for the feed water heater ex- 30 tended through the rear wall of the setting and connected with the drainage pipe for the boiler outside of the said rear wall, sub- stantially as described. 30
4. The combination with a boiler setting 35 and a boiler supported thereby to form a chamber between the rear end of the boiler and the rear and top walls of the setting, of a feed water heater located in said chamber, and pipes connecting the boiler near the
- bottom thereof with the heater above the 40 level of the bottom of the boiler to obtain a substantially progressive upward flow of water from the point where it leaves the boiler to the point where it enters the boiler, substantially as described. 45
5. The combination with a boiler setting and a boiler supported thereby to form a chamber between the rear end of the boiler and the rear and top walls of the setting, of a feed water heater located in said chamber, 50 and pipes located within the setting and connected with the boiler near its front end and with said heater above the level of the bottom of the boiler for the circulation of cold water therethrough, substantially as de- 55 scribed. 55
6. The combination with a boiler setting and a boiler supported thereby to form a chamber between the rear end of the boiler and the rear and top walls of the setting, of a feed water heater located in said chamber, 60 and pipes connecting the boiler near the bottom thereof with the heater above the level of the bottom of the boiler to obtain a substantially progressive upward flow of 65 water from the point where it leaves the boiler to the point where it enters the boiler, a blow-off pipe for said boiler independent of the circulating system which includes the boiler and heater, substantially as described. 70

In testimony whereof, I have signed my name to this specification in the presence of two subscribing witnesses.
